CLAIM

The ornamental design for a toe strengthening and mobilizing device, as shown and described.

DESCRIPTION

FIG. 1 is a front perspective view of a toe strengthening and mobilizing device showing the new design.

FIG. 2 is a top perspective view of the toe strengthening and mobilizing device.

FIG. 3 is a front elevational view of the toe strengthening and mobilizing device.

FIG. 4 is a rear elevational view of the toe strengthening and mobilizing device.

FIG. 5 is a left side elevational view of the toe strengthening and mobilizing device.

FIG. 6 is a right side elevational view of the toe strengthening and mobilizing device.

FIG. 7 is a top plan view of the toe strengthening and mobilizing device; and,

FIG. 8 is a bottom plan view of the toe strengthening and mobilizing device.

1 Claim, 2 Drawing Sheets
